UNITED STATES PATENT OFFICE.

LOUIS BURGER, OF CHICAGO, ILLINOIS.

DESIGN FOR A SPOON.

SPECIFICATION forming part of Design No. 22,254, dated March 7, 1893.

Application filed January 3, 1893. Serial No. 457,172. Term of patent 3½ years.

To all whom it may concern:

Be it known that I, LOUIS BURGER, a citizen of the United States, residing at Chicago, county of Cook, and State of Illinois, have invented and produced a new and original Design for Souvenir Spoons, &c., of which the following is a specification, reference being had to the accompanying drawing, which is a fair illustration thereof.

- 10 The leading feature of my design consists in the handle, the end-portion of which is irregular and rounded in outline as shown in the drawing, within which outline is a representation of Columbus standing with one arm
15 crooked and carrying a scroll in his other hand. The remainder of the shank portion

of the handle has an outline made up of the representation of a medallion, adjacent to which is a shield having three faces, between which shield and the inner end of the handle 20 the shank has the form of a curved slender stem.

What I claim as new, and desire to secure by Letters Patent, is—

The design for the handle of a souvenir 25 spoon &c., substantially as shown and described.

LOUIS BURGER.
